MOUNTING FOR FAN ASSEMBLIES

Ralph K. Odor, Edmond, Okla., assignor to The
Vornado Trust, Oklahoma City, Okla., a fiduci-
ary trust of Oklahoma

Application March 3, 1945, Serial No. 586,812

7 Claims. (Cl. 248—26)

1

This invention relates to a mounting for electric fans and more particularly to devices for adjustably supporting the motor-fan unit.

A principal object of the invention is to provide a mounting of simple and efficient form and including novel and effective means for absorbing vibrations and for adjusting the blade to different angles as may be required.

The invention further resides in the novel structural details and arrangements hereinafter described and illustrated in the attached drawings wherein:

Figure 1 is a sectional elevational view illustrating a mounting made in accordance with the invention;

Figure 2 is a front elevational view of the motor-fan unit;

Figure 3 is a view in perspective of the principal element of the mount structure, and

Figure 4 is a fragmentary rear elevational and partial sectional view showing the element of Figure 3 in its relation to the fan motor.

With reference to the drawings, the fan unit comprises essentially an electric motor 1 and an impeller 2 in the form, in the present instance, of a fan of the radial blade type. The impeller as shown is attached to the motor shaft in proximity to one end of the motor housing. In accordance with the invention, the motor 1 is supported within an annular member 3, the general form of which is best illustrated in Figure 3. This member consists essentially of a metallic sleeve 4 which is split as indicated at 5, the terminal edges of the sleeve at opposite sides of the split extending outwardly to form terminal flanges 6—6. These flanges are apertured for reception of fastening elements hereinafter described. The sleeve 4 is provided with four corresponding openings, one of which is shown at 7 in Figure 3, and at each of these openings is attached, as by welding, an internally threaded tubular element which projects outwardly in a generally radial direction beyond the outer surface of the sleeve. These four tubular projections have been designated in the drawings by the reference numerals 8, 9, 10 and 11 respectively. It will be noted by reference to Fig. 4 that the openings 7 and the aforesaid associated tubular elements are not uniformly spaced about the center of the sleeve 4, the members 8 and 9 each being 45° removed from and at opposite sides of the vertical, and the members 10 and 11 being only 30° removed from the vertical. The purpose of this arrangement will be hereinafter described.

With further reference to Fig. 4, it will be noted that in each of the members 8, 9, 10 and 11 is established a rubber or other resilient member 12. The outer cylindrical ends of these members 12 are preferably confined under light compression within the associated cylinder and the inner somewhat tapered ends of the said members 12 pro-

2

ject inwardly somewhat beyond the inner surface of the sleeve 4. The members 12 are retained in their respective cylinder retainers by a threaded disc-like closure element 13 which is threaded into the outer end of the cylinder, the said disc closure being provided with a socket 14 for reception of a turning wrench. The position of the resilient member 12 in the cylinder and the extent to which it projects beyond the inner surface of the member 4 may be adjusted through the medium of the threaded retainer 13. Each of the members 12 is provided with a central bore or recess for reception of a motor-retaining member 15, this member taking the form of a washer-like disc 16 having at its outer side a stem 17 which projects into the bore 18 and having at the opposite side a shorter projection 19 which enters a recess 20 in the outer surface of the housing of the motor. This is clearly shown in Fig. 4. By this means the motor 1 is supported within the sleeve 4 in spaced relation to the latter and in suspension between the four resilient members 12.

It is to be noted in this respect that the tapered form of the inner ends of the members 12 provide clearance between the said inner ends and the walls of the associated cylinders, 8, 9, 10 and 11, respectively, thus affording a degree of freedom for flexure of said members in the transverse direction, that is to say, laterally of the axial centerlines of said cylinders. The aforesaid clearance also affords freedom for compression of the members 12 radially of the sleeve. As previously indicated, the initial compression of the members 12 against the motor housing may be regulated by adjustment of the threaded closure elements 13.

The sleeve 4 is adapted to be supported upon a curved strap-like member 21, this member preferably being made of a material having some degree of resilience to thereby provide additional means for absorption of vibration in the motor-fan unit. One end of the strap 21 is secured between the flanges 6—6 of the sleeve 4 by means of bolts 22 which pass through at the apertures 23 in the flanges and through registering apertures in the member 21. The member 21 is slideably supported in the upper end of a standard 22, said upper end being slotted for reception of the strap element 21 and also for reception of a pair of clamping elements 24 and 24a, which engage the opposite faces respectively of the member 21 and which may be clamped solidly upon the said member through the medium of a screw 25 threaded into the top of the standard. By adjustment of the member 21 in the standard 22, the angularity of the fan with respect to the horizontal may be regulated as required for directing the air in the desired path. As shown in Fig. 1 the standard 22 comprises a base 27 sufficiently heavy and extending to afford a stable support for the fan assembly, and a tubular upright member 28 which is secured to the base and which telescopically re-

ceives the upper member 28 of the standard. This member 28 may be adjusted for height within the member 28 and is held in adjusted position by means of a locking screw 30.

In the present instance the fan assembly comprises a pair of funnel-shaped tubular flanges 31 and 32 which are calculated to increase the efficiency of the fan in accordance with the principles set forth in my United States Patent No. 2,330,907, dated October 5, 1943. For the purpose of supporting these flanges 31 and 32, the sleeve 4 is provided with radial arms 33, which are arranged with their narrow sections in planes intersecting the axis of the assembly so as to afford a minimum resistance to passage of air through the flange 31 and to the outer ends of which the said flange is secured. Similar arms 34 are attached to and extend from the outside of the flange 31 as supporting means for the flange 32.

The form and functional nature of the mounting will be apparent from the foregoing description. It is to be noted particularly that the device affords a strong and stable mounting for the relatively bulky fan assembly including the motor 1, the fan 2, and the tubular flanges 31 and 32, and provides for absorption of the vibrations set up in this assembly during operation of the fan as well as for ready adjustment of the fan to different angular positions on the supporting standard. It is to be noted that the resilient members 12 operate in shear to take up vibrating movements of the motor-fan unit of both torsional and axial character, and in compression to absorb the radial vibrations. The members thus exhibit high efficiency in the vibration absorbing function. The irregular spacing of the resilient members described above has the effect of damping the vibrations.

The structure lends itself readily to manufacture from sheet materials and to fabrication by welding methods. The sleeve 4, for example, may be made of sheet metal stock of sufficient gage to insure substantial rigidity, and the cylindrical elements 8, 9, 10 and 11 may be sections of tubing and may be welded in place in the apertures of the sleeve 4. Similarly, the flanges 6-8 may, if desired, be separately formed and welded to the extremities of the sleeve 4, and the arms 33, formed also from sheet metal stock, may be welded to the surface of the sleeve. The arms 33 and 34 may be secured in any desired manner to the flange elements 31 and 32, and the latter preferably are of a character to reduce to a minimum resonance arising from vibration.

There may be some modification in the details of construction without departure from the invention as defined in the appended claims.

I claim:

1. In a mounting for electric motors, a support structure having an annular series of substantially radial pockets, a resilient member seated in and projecting from each of said pockets toward the center of the annulus so as to bear against the casing of and, jointly, to resiliently support said motor in the structure, and an element embedded in each of said members and projecting radially from the inner end thereof for interlocking engagement with the said casing to anchor the motor to said members.

2. A mounting for electric motors as defined in claim 1, wherein the said anchor element consists of a radially disposed pin of relatively small diameter as compared with the associated resilient member.

3. A mounting for electric motors as defined in

in claim 1 wherein the said anchor element consists of a radially disposed pin of relatively small diameter as compared with the associated resilient member, said pin having intermediate its ends a transverse shoulder for seating engagement with a confronting surface of said member.

5. A mounting for electric motors as defined in claim 1 wherein each of the said resilient members is tapered so that the inner end thereof is of materially lesser diameter than the outer end.

10 6. A mounting for electric motors as defined in claim 1 wherein each of the said resilient members is tapered so that the inner end thereof is of materially lesser diameter than the outer end and wherein further the resilient member is unconfined and free for transverse movement in all directions over the major portion of its length from the said inner end thereof.

15 7. A mounting for electric motors, a support structure having an annular series of substantially radial pockets, a resilient member seated in and projecting from each of said pockets toward the center of the annulus so as to bear against the casing of and, jointly, to resiliently support said motor in the structure, a pin of relatively small diameter embedded in each of said members and projecting radially from the inner end thereof for interlocking engagement with said casing to anchor the motor to said members, each said member being unconfined and free for transverse movement in all directions over the major portion of its length from the inner end thereof, and the embedded portion of the associated pin being confined substantially to the said free portion of the member.

20 8. In a mounting for electric motors, a support structure having an annular series of substantially radial pockets, a resilient member seated in and projecting from each of said pockets toward the center of the annulus so as to bear against the casing of and, jointly, to resiliently support said motor in the structure, said members being tapered so that the inner ends thereof are of materially lesser diameter than the outer ends, and said members being unconfined and free for transverse movement in all directions over the major portion of their lengths from the inner end thereof, an element embedded in each of said members and projecting radially from the inner end thereof for interlocking engagement with said casing to anchor the motor to said members, and adjustable means for placing the members under longitudinal compression between the bottoms of the said pockets and the casing of the motor.
